His attorney.

UNITED STATES PATENT OFFICE.

EDWARD P. COLE, OF CHICAGO, ILLINOIS.

CASING FOR METAL THERMOMETERS AND THE LIKE.

1,348,210.

Specification of Letters Patent.

Patented Aug. 3, 1920.

Application filed August 2, 1919. Serial No. 314,939.

To all whom it may concern:

Be it known that I, EDWARD P. COLE, a citizen of the United States, residing at Chicago, in the county of Cook and State of Illinois, have invented certain new and useful Improvements in Casings for Metal Thermometers and the like, of which the following is a specification.

My invention relates to a casing which in the particular embodiment illustrated in the accompanying drawings and hereinafter described is designed to inclose a bi-metal thermometer used for measuring temperatures of several hundred degrees, such as are largely used for indicating the heat of ovens for baking food in stoves and ranges for domestic or commercial purposes. The particular construction of the thermometer has nothing to do with my present invention, which relates entirely to a casing adapted to receive and support such a thermometer properly in a wall of the oven structure, or serve any similar purpose. The object of my invention is to provide a simple, attractive and desirable casing for such a device which shall be cheap to manufacture, easy to apply to the oven upon which the thermometer is to be used, and which shall be well adapted to serve the purposes for which it was designed. With this object in view my invention resides in the construction, structural arrangement and organization of the members which make up my novel and improved casing, as hereinafter explained and described, the essential elements of my invention being more particularly pointed out in the appended claims.

Figure 1 of the drawing forming a part of this specification is a face view of a casing embodying my invention; Fig. 2 is a perspective of the lower or box member of the casing; Fig. 3 is a perspective of the dial member; Fig. 4 is a perspective of the cover frame, showing the underside thereof; and Fig. 5 is a central transverse section of the casing.

The same reference characters indicate the same parts in all the figures of the drawing.

The bottom or box member of my novel casing, see Fig. 2, may be conveniently formed of a sheet metal blank cut and bent to form a rectangular bottom section 1 and connected flanges or members forming sides 2 and ends 3, each of the latter having an outwardly extending ear 4 in the same plane as the top of the sides 2. In the present in-

stances, as shown, the bi-metal strip 5 of the thermometer device is secured to a block 6 fixed to the bottom of the casing, and is operatively connected with the indicating hand 7 pivotally mounted upon a post 8 also secured to the bottom of the casing. A slot 9 in the bottom 4 is provided adjacent the strip 5 to expose the latter to the heat of the oven.

The dial member 10, see Fig. 3, is also formed of a rectangular sheet metal blank which near each end is formed with a fold or crimp 11 adapted to fit over and seat upon the upper edges of the ends 3 of the box member. The intermediate portion of the dial plate member is formed with a slot 12 extending from one side edge toward the center, to receive the post 8, and may be enameled or finished in any suitable manner and provided with a scale to coöperate with the indicating hand. Outside the line of the crimps 11 the flat end portions 13 lie on top of the ears 4, and the parts 13 and 4 are formed with registering orifices 14 to admit bolts by means of which the casing is secured to the oven. These end portions 13 may be omitted, however, if desired. It will be understood the oven wall is formed with an opening just large enough to receive the box member as far as the ears 4, and that the casing is secured to the oven wall by bolts extending therethrough.

The cover frame 15, which may be a metal casting, is formed with a central display opening 16 exposing the dial scale and hand 90 and adjacent its margin bears upon and surrounds the outer edge of the dial member 10. The proportions and arrangement of the parts is such that between the top of the folds 11 and the inner face of the cover 95 frame there will be a space of proper size for the reception of a cover glass 17 for protecting the indicator hand.

The inner side of the cover frame 15 is formed with a pair of opposite bosses tapped 100 for the reception of the threaded ends of headed screw bolts 18 which extend from the inside of the oven wall through the orifices in the parts 13 and 4 before mentioned, and which serve to secure the casing in place in 105 the oven wall.

It is obvious that while my casing is well adapted for the particular use above described, it may be adapted to incase any desired article and be secured in an opening 110 in any kind of wall or other structure in a similar manner.

I claim:

1. A casing comprising a box member formed with a bottom and side and end members, one pair of opposite members being longer than the other, a dial member formed with parallel projecting folds arranged to fit over said longer members, and a cover frame formed with a display opening and having marginal flanges arranged to receive said dial member.
2. A casing comprising a box member formed with a bottom and side and end members, one pair of opposite members being longer than the other, and being formed with ears projecting parallel with said bottom and lying in the plane of the free edges of the other sides, a dial member formed with parallel projecting folds arranged to fit over said longer members and also arranged to seat upon said ears of the longer members and the edges of the other members, and a cover frame formed with a display opening and having marginal flanges arranged to receive said dial member.
3. A casing comprising a box member formed with a bottom and opposite members forming ends, said members being formed with outwardly extending ears parallel with said bottom, a dial member arranged to seat against said outwardly extending ears of the ends of the box member, said dial member and outwardly extending ears being formed with registering orifices, and a cover frame formed with a display opening and having marginal flanges arranged to receive the edges of said dial member.
4. A casing comprising a rectangular box member formed with a bottom and opposite marginal members forming ends, a rectangular dial member formed with parallel projecting folds arranged to fit over said end members and with an indicator post slit intermediate said end members and parallel therewith, and a cover frame formed with a rectangular display opening exposing the inner end of said slit, and provided with marginal flanges arranged to receive the edges of said dial member.
5. A casing comprising a sheet metal bottom formed with at least two opposite marginal members, a sheet metal dial member formed with projecting folds arranged to fit over said marginal members, and a cover frame formed with a display opening and arranged to engage the margin of said dial member.
6. A casing comprising a sheet metal bottom formed with at least two opposite marginal members, a sheet metal dial member formed with projecting folds arranged to fit over said marginal members, a cover frame formed with a display opening bearing upon said dial member adjacent its edges, and a glass cover plate arranged between said cover frame and the folds of said dial member.
7. A casing comprising a rectangular sheet metal box member formed with a bottom and opposite members forming ends, a rectangular dial member formed with parallel projecting folds arranged to fit over said ends, and a cover frame formed with a display opening and having flanges arranged to receive the margin of said dial member.
8. A casing comprising a rectangular sheet metal box member formed with a bottom and opposite members forming ends, a rectangular dial member formed with parallel projecting folds arranged to fit over said ends, a cover frame formed with a display opening and having flanges engaging the margin of said dial member, and bolts engaging said cover frame.

EDWARD P. COLE
